UNITED STATES PATENT OFFICE.

EDWD. L. SEYMOUR, OF NEW YORK, N. Y., ASSIGNOR TO W. O. BOURNE.

APPARATUS FOR SIFTING.

Specification of Letters Patent No. 13,449, dated August 14, 1855.

To all whom it may concern:

Be it known that I, EDWARD LOUIS SEYMOUR, of the city and State of New York, chemist, have invented a new and useful Apparatus or Machine for Sifting; and I hereby declare that the following is a full, clear, and exact description of the construction and operation of the same, reference being had to the annexed drawings, making part 10 of this specification.

My invention and improvement consist, first, in the peculiar arrangement and construction of a cylindrical sifting apparatus, for metallurgical and other purposes, which 15 I call the "compound tubular rotary sifter," consisting as it does of two, three, four, five or more cylindrical or tubular sieves of various dimensions, placed one within the other, and so contrived as to be capable of being 20 easily set into a rotary motion around one common center or axis; and while thus rotating, as one body, to sift out, in one and the same operation, and within a very narrow compass, any desirable number of dif- 25 ferent sizes, with the greatest possible rapidity; combining, therefore, every possible advantage and facility, in all such technical manipulations or processes, in which large quantities of ore, rock, minerals or mineral 30 earths, sands, gravels, &c., grain or powder of any description or nature have to be sifted and subdivided into a variety of corresponding sizes of their respective atoms parts or particles. The first or center-sieve being 35 the coarsest; and the last or outermost being the finest, the sifting out of all the sizes required is performed from the center of the apparatus toward its surfaces, that is, from the coarsest to the finest. Secondly, in the 40 peculiar construction and arrangement of the frames or skeletons, around which the sieve-cloths have to be spread and fastened. Such frame or skeleton I call the compound helicoidal frame. I make it of a series of 45 metallic rods or strips, wire or any other convenient material, so contrived as to present a series of equidistant helicoidal surfaces within each of the tubular sieves and receptacles; making the planes of such heli- 50 coidal surfaces the more incline toward the one center common to all, the greater the

diameter of their respective tubular sieves and receptacles, a set of which, when placed one within the other, and attached to a common rod or axis around which to rotate; or 55 with any other convenient mode capable of producing the same rotary motion, constitute, as aforesaid, my "compound tubular rotary sifter."

The object of the "compound helicoidal frame" is to make the parts, particles or atoms of the ore or matter being sifted, spread most uniformly; and travel the faster over the surfaces of their respective sieves and "discharging tubes or receptacles, 60 the larger the space they have to go through.

On reference to the accompanying drawings the mode of constructing a "compound tubular rotary sifter," intended for four different sizes, will be easily understood. 70

Figures 1, 2, 3, and 4 represent the "compound helical frames"; the space between X and Z in Figs. 1, 2, and 3 to be covered with sieve-cloth of desirable meshes or numbers; the coarsest, as a matter of course, for 75 the first or center sieve; the finest for the third, or, if a greater number of sieves be used, for whichever is the last or outermost sieve; the remaining surface of the frames to be covered with sheet iron, or any other 80 convenient material, to form in each sieve a tubular receptacle, or rather, "discharging conduits." The spaces covered with sieve-cloth are to be longer on each frame from the inner to the outermost; that is to say, 85 the outer sieves require a greater length of sifting surface, so as to prevent any portion of the stuff which falls, during the process, from one sieve into the other, to be discharged unsifted; while the tubes or "dis- 90 charging pipes" have inverse lengths, for the purpose of delivering each size separately. Fig. 4, is to be entirely surrounded with sheets of metal (or other material answering the purpose) forming the last 95 "tubular receptacle or conduit," and discharging the last or finest size.

When the various sieves are put together for working, viz., one over the other, they are kept in their positions by means of 100 screws, bolts or pins, uniting their respective flanges, at one end; while, at the other end,

the proper spaces between the "tubular discharging pipes or conduits" of the respective sieves can be regulated and maintained by means of pins, wedges or otherwise.

5 What I claim as my invention in the above described rotary sifter is—

The several cylindrical sieves one within

the other provided with conduits, so arranged as to deliver the proceeds continuously substantially as described.

E. LOUIS SEYMOUR.
